UNITED STATES PATENT OFFICE.

JAMES G. BLUNT, OF SCHENECTADY, NEW YORK.

LOCOMOTIVE WHISTLE.

Application filed November 19, 1927. Serial No. 234,323.

This invention relates to locomotive whistles, and particularly to whistles of such character as can be operated, at the option of the engineer, either by mechanical means, such as rods and levers, or by fluid pressure, and has for an object to provide a whistle of such type, which embodies a minimum number of parts; which is of compact, durable, and economical construction; and which is highly efficient in operation.

There have heretofore been used, in common practice, locomotive whistles, adapted to be operated from the cab, either mechanically, such as by levers and rods; or by fluid pressure. Such whistles have embodied a large number of complicated parts, and a large number of jointures, which must be maintained steam tight, and, as a result, have been expensive to manufacture, and difficult to maintain in working order. The present invention provides a whistle, free from the objections noted.

The improvement claimed is hereinafter fully set forth.

In the accompanying drawing: Figure 1 is a vertical section, taken on the line *a a* of Fig. 2, of a whistle embodying the invention; Fig. 2, a transverse section of the same, taken on the line *b b* of Fig. 1; and, Fig. 3, a similar section, taken on the line *c c* of Fig. 1.

In the practice of the invention, referring descriptively to the specific embodiment thereof which is herein exemplified, the chime member, 10, is preferably formed as an integral casting, and comprises an outer cylindrical tube, 10^a, and an inner cylindrical tube, 10^b, disposed concentrically of the outer tube. The space between the two tubes is divided into a plurality of chime chambers, 10^c, by radially extending partitions, 10^d. The inner tube is prolonged to constitute a cylinder, 10^e, in which reciprocates the piston, 11, of a piston member. Internal screw threads, 10^f, are cut, at the bottom of the inner tube, for the attachment of a bowl member, 12. The lower end of the inner tube is also finished with a horizontal circular outwardly extending flange, 10^g, adapted to fit within the top of a bowl, 12^a, of the bowl member, 12, with sufficient clearance from the inner face of the side wall of the bowl to provide a passageway, 10^h, for steam to blow the whistle. A passageway, 10ⁱ, for steam, leads through one of the chime chambers, 10^c, into the upper end of the cylinder, 10^e.

The bowl member, 12, is preferably formed

as an integral casting, and comprises the bowl, 12^a; a threaded nipple, 12^b, extending above the bowl, by which the bowl member is attached to the chime member; and a valve body, 12^c, comprising a valve seat, 12^d, for the valve, 13, and a cylindrical housing in which the valve stem, 13^a, makes a snug sliding fit. The exterior of the housing is provided with screw threads, 12^e, by which the whistle is directly connected to the shell of a boiler. An outwardly projecting, hollow extension, 12^f, is provided at one side of the housing, in which is pivoted, on the pin, 14, the bell crank lever, 14^a. The lower arm of the lever projects through the extension, 12^f, into a slot, 13^b, formed in the valve stem, 13^a. A stud, 12^g, is screwed into one side of the housing, and extends into the slot, 13^b, of the valve stem, to provide a stop, adapted to prevent the valve and stem from dropping into the boiler, when the lever is removed.

The valve stem, 13^a, is formed with two passageways, 13^c, through which steam passes from the boiler to the bowl, 12^a, when the valve, 13, is open. Preferably the valve, 13, and its stem, 13^a, are formed as an integral casting.

This piston member is preferably formed as an integral casting, and comprises the piston, 11, which has the form of a relatively long hollow cylinder, and a stem, 11^a, adapted to bear on the upper end of the valve stem 13^a.

The area of the piston, 11, is greater than that of the valve, 13, so that boiler steam, acting against the piston, will cause the piston to unseat the valve.

The operation of the whistle is as follows:

When the engineer desires to operate the whistle by fluid pressure, he opens a suitable control valve, mounted in the cab, admitting boiler steam through the passageway, 10ⁱ, into the cylinder, 10^e, whereupon the piston, 11, will be forced downwardly, unseating the valve, 13. Boiler steam will then pass through the passageways, 13^c, of the valve stem, into the bowl, 12^a, and thence through the passageway, 10^h, causing the chime member to resonate. When the engineer closes off steam from the cylinder, 10^e, the valve, 13, will close, under the pressure of boiler steam, returning the piston, 11, to normal position. When the engineer desires to operate the whistle by manual pressure, he moves a suitable lever, mounted in the cab, whereupon the lower arm of the bell crank lever will move the valve, 13, to open position.

From the foregoing description, it will be apparent that the improved whistle consists of but five major parts, viz: a chime member; a piston member; a bowl member; a valve member; and a bell crank lever, which parts are preferably formed as integral castings, and can be inexpensively manufactured and assembled. Further important advantages of the improved construction are its great durability, and the small number of jointures which require to be maintained steam tight.

The invention claimed as new and desired to be secured by Letters Patent is:

15. 1. In a whistle of the character described, the combination of a bowl shaped member; a tubular casing projecting from the convex side of the member, opening at one end into the concave side of the member, the opposite 20 end being adapted for connection with a sound generating fluid supply conduit; a valve seated in said opposite end, adapted to be actuated to open in a direction away from said member to admit the fluid, and when released, to close under the pressure of said 25 fluid; a cylinder at the concave side of said member, communicating with the tubular casing; a chime member, overhanging the cylinder; a piston within the cylinder; means, 30 extending through said casing, operatively connecting the piston and valve, all of the above mentioned parts being axially aligned with one another; a conduit for supplying actuating fluid under pressure to the far end 35 of the cylinder relative to the valve, whereby the piston may be actuated in a direction to

open the valve, said piston being returned by the closing of the valve when the actuating pressure is removed; and means whereby the valve may be manually operated.

2. In a whistle of the character described, the combination of a bowl shaped member; a tubular casing projecting from the convex side of the member, opening at one end into the concave side of the member, the opposite 40 end being adapted for connection with a sound generating fluid supply conduit; a valve seated in said opposite end, adapted to be actuated to open in a direction away from 45 said member to admit the fluid, and when released, to close under the pressure of said fluid; a chime member disposed at the concave side of the bowl shaped member; a cylinder at the concave side of said member, between said bowl shaped member and chime 50 member, communicating with the tubular casing; a piston within the cylinder; a conduit for supplying actuating fluid under pressure to the far end of the cylinder, relative to 55 the valve; a two part valve stem extending through said tubular casing, having its opposite ends connected, respectively, to the piston and valve, said stem parts co-acting to open the valve when the actuating fluid is applied, and to close the piston by the pressure 60 of the generating fluid when the pressure of the actuating fluid is released; and means operatively connected to the valve stem part connected to the valve, whereby the valve 65 may be manually operated independently of the piston.

JAMES G. BLUNT.
